MACHINE FOR SIMULTANEOUSLY PRINTING WORDS AND FIGURES

Original Filed April 10, 1922 2 Sheets-Sheet 2

UNITED STATES PATENT OFFICE

EDWARD JOHN WARD, OF BISHOPSGATE, LONDON, ENGLAND, ASSIGNOR TO THE INVICTA WRITER, INC., OF NEW YORK, N. Y., A CORPORATION OF DELAWARE

MACHINE FOR SIMULTANEOUSLY PRINTING WORDS AND FIGURES

Application filed April 10, 1922, Serial No. 551,439, and in Great Britain November 28, 1921. Renewed October 14, 1927.

This invention relates to an improved form of that type of machine which is adapted to simultaneously print words and figures denoting the same amounts and in which depressible keys of different values are employed to control mechanism adapted to turn parallel rollers on which the letters forming the words and the figures used for printing are mounted.

10 The chief feature of my invention is that I employ longitudinal movable bars having racks which actuate the above mentioned mechanism and which bars are normally held against the tension of springs, but are released from the holding means and drawn by their springs distances which vary in accordance with the key selected to effect the release, said bars thereby causing the racks to actuate the mechanism and rotate the type-carrying rollers a distance corresponding to the selected key.

15 The invention also includes improved means for actuating the tens and hundreds columns as well as simplified mechanism for repeat printing without resetting the keys and for returning the said bars and releasing the keys at the completion of the required printing of any sum whether it has been printed once or repeatedly.

20 In my machine I use a pivoted platen and actuate it by a lever to move it to and from the printing surfaces of the rollers over which a suitable inking ribbon is arranged. The mechanism actuating the lever and the platen is of simplified form and easily operated.

25 I will now describe my invention with reference to the accompanying drawings in which Fig. 1 may be described as a longitudinal section of one form of the machine and Fig. 2 as a plan view, the machine shown being one for printing simultaneously in words and figures money values in pounds, shillings and pence.

30 In these drawings the frame of the machine is indicated at 1, the whole case of

the machine not being shown for the sake of clearness. In the frame 1 are mounted on shafts 2 and 3 two printing rollers 4 and 5, one, preferably the upper, being adapted for printing the money values in words and the other in figures. The printing rollers are each divided into a number of separate sections as indicated in Fig. 2 in connection with the upper rollers 4, by the references 50 *a, b, c, d, e, f*, and by the references *g, h, j, k, l, m*, for the lower rollers 5. On the section *a* are provided the words from "one" to "eleven" for the pence, on the section *b* the words from "one" to "nineteen" for the shillings, on the section *c* the words from "one" to "nine" and portions of the words from "eleven" to "nineteen," on the section *d* the words for the tens of pounds from "twenty" to "ninety" and the word "and," portions of the words from "ten" to "nineteen" not provided on section *d*, on the section *e* the words from "one hundred" to "nine hundred" and from "one thousand" to "nine thousand," and on section *f* the words from "one thousand" to "nine thousand." When these sections are 60 turned in the manner hereinafter described it will be seen that the sections may be set to any amount for a sum of money from "one penny" to "nine thousand, nine hundred, ninety-nine pounds, nineteen shillings, eleven pence".

65 The sections of the roller 5 are much narrower than the sections of the roller 4 and are preferably arranged towards one side, as shown for example by dotted lines in Fig. 2. 70 On the section *g* are provided the figures "0" to "11," on the section *h* the figures "0" to "19," on the section *j* the figures "0" to "9," and again from "0" to "9" on the section *k* the figures "0," "2" to "9" and an additional 75 "0" and then a series of "1" ten times, on the section *l* the figures "0" to "9" and again "0" to "9" and "20," "30," "40," "50," "60," "70," "80," and "90," and on the section *m* the figures "1" to "9" and again "1" to "9." These 80 85 90

sections are adapted to be turned in synchronism with the sections of the roller 4 so that the words and figures are set simultaneously.

In order that the marking of the sections 5 for the units and tens of pounds may be fully understood the following is given as an example of a convenient arrangement in which the words and figures may be provided on sections *c*, *d*, *j*, *k*.

10	Section <i>d</i>	Section <i>c</i>	Section <i>k</i>	Section <i>j</i>
AND	XXXXXX	0	X	
NINETY	NINE	9	9	
EIGHTY	EIGHT	8	8	
SEVENTY	SEVEN	7	7	
15 SIXTY	SIX	6	6	
FIFTY	FIVE	5	5	
FORTY	FOUR	4	4	
THIRTY	THREE	3	3	
TWENTY	TWO	2	2	
20 XXXXXX	ONE	x	1	
XXXXXX	XXXXX	0	0	
TEN	XXXXX	1	0	
ELE	VENXX	1	1	
25 TWE	LVEXX	1	2	
THIR	TEEN	1	3	
FOUR	TEEN	1	4	
FIF	TEEN	1	5	
SIX	TEEN	1	6	
30 SEVEN	TEEN	1	7	
EIGHT	TEEN	1	8	
NINE	TEEN	1	9	

Between the sections *g* and *h* and *h* and *j* 35 free spaces are left which are preferably filled by distance sections *y* and *z*, which may be left plain, or if desired may be provided with full stops or =, or any other suitable sign to form a division in the figure amount 40 between the pounds, shillings and pence.

The separate sections are mounted on concentric sleeves 6, freely rotatable on the shafts 2, 3, and are provided at their outer ends with toothed wheels 7. The toothed wheels 7 45 of both rollers are simultaneously and equally rotated by toothed wheels 8, gearing with toothed wheels 9, driven by toothed wheels 10. The toothed wheels 10 are fixed to sleeves 11 concentrically mounted on a shaft 12. To the 50 inner ends of the sleeves 11 are fixed toothed wheels 13 adapted to be rotated by racks 14 forming the continuation of control bars 15.

It will be seen that there is a separate control bar 15 under each set of keys 16 and one 55 of these bars and its control by a set of keys for units will now be described in detail. The bars 15 is preferably hinged to the rack 14 at 17, so that while the rack is only capable of sliding movement, the bar may both slide 60 horizontally and be moved vertically. The rack 14 is provided with a downwardly projecting arm 18 to which is attached a spring 19 normally tending to pull the bar and rack inwardly. The bar 15 is held in its normal 65 horizontal position by a leaf spring 20, and

near its forward end is provided with a step or stop 21 normally engaging with the front plate 22 of the frame so as to prevent the spring 19 from pulling the bar 15 inwardly until the latter is released as hereinafter described. 70

Each of the keys 16 is supported by a light spring 23 and each key 16 is adapted when pressed down to depress the bar 15 so as to free the step 21 from the front plate 22 and 75 allow the spring 19 to pull the bar inwardly and in doing so cause the rack 14 to rotate its corresponding wheels 13, 10, 9, 8, 7, and thus the corresponding sections of the rollers 4 and 5. The bar 15 is provided with lateral 80 projections or stops *n*, *o*, *p*, *q*, *r*, *s*, *t*, *u*, *v*, *w*, *x* appropriately arranged so as to contact with the foot of the correspondingly lettered keys which have been depressed, it being understood 85 that the positioning of these stops is such that the bar 15 and rack 14 will be allowed to move a distance which will turn the rollers 4, 5 to the value of the operated key. The projections *n*...*x* may be all arranged on one side of the bar 15 or they may be arranged 90 alternately on opposite sides, the keys 16 being suitably shaped at their lower ends so that they will project into the path of their corresponding projection when depressed. It has, however, been found desirable to arrange 95 the stops alternately on opposite sides of the control bar, some of the projections being arranged near the upper edge of the control bar and others near the bottom edge thereof, whilst the lower ends of the keys project 100 down varying distances. With such an arrangement there is no likelihood of a wrong stop of the control bar coming into contact with the lower end of the key 16 which has been depressed, and thus preventing the required movement of the bar to bring the correct portion of the sections of the rollers 4, 5 into the operative position. Near their lower ends the keys 16 are provided with shoulders 105 23^a which are adapted to depress the control bar 15 when the key is pressed down.

The control bars 15 in the tens columns of the shillings and pence are not provided with projections similar to those on the units bar, nor are they provided with racks, but are 110 simply hinged to links 56 or connected to springs 19 as desired.

The control bars in the units columns of the pounds, shillings and pence, and in the hundreds columns of the pounds are also provided with projections *o'*, *p'*, *q'*, *r'*, *s'*, *t'*, *u'*, *v'*, *w'*, *x'* which are adapted to come into operation with their correspondingly lettered keys when figures and words between 10 and 19 inclusive are to be printed as will be described later. 120

The lower ends of the keys 16 also pass through a slotted plate or bar 24 which is capable of sliding movement and is normally held in such a position by a spring 25 that 130

the keys can be depressed without obstruction. The keys 16 have stems of such a shape that when one of the keys is depressed the plate 24 is pressed outwards against the action of the spring 25. The plate 24 then rides over a stop 26 on the key stem so that the key is prevented from rising under the action of its spring 23, as shown in dotted lines in connection with the key T. The key stems are also provided with stops or projections 27 which are of such a size as to just pass through the slots in the plate 24 when this is in its normal position. As will be seen in the drawing, the upper portions 28 of the key stems are wider than the lower portions 29 plus the depth of the stop 27, so that when one key has been depressed and moved the plate 24 outwards none of the other keys can be depressed as their projections 27 cannot pass through the slots in the plate 24.

In the "tens" columns of the pounds, shillings and pence columns the "1" key is provided with a lateral arm 29^a which extends both over the bar 15 for the tens column and the bar 15 for the units column. When it is desired to print numbers and their corresponding words between 10 and 19 the "1" key in the "tens" column is depressed. By means of the lateral arm the bars 15 for both the units and tens columns will be depressed, and as this arm does not co-operate with any stop on either of the two bars 15, these bars will be pulled inwards by their springs 19 until a second projection 30 on the bar 15 for the units comes against the front plate 22 of the frame. The bar 15 for the units is also provided with a lateral pin 31 so arranged that when the projection 30 comes against the plate 22 a projection 32 on the bar 15 for the tens will also prevent this latter bar from further inward movement. The inward movement of the two bars thus causes the printing rollers 4, 5 to be turned through a distance beyond the markings corresponding to the keys 16. The key for the required unit is now depressed and the two bars 15 are now pulled inwards simultaneously until the corresponding projection o' . . . x' comes against the lower end of the depressed key, when the printing rollers will be in the required position for printing the required number between 10 and 19. For example, if the number 16 were required, the key R would be depressed and the bars 15 would be pulled inwards until the stop r' came in contact with the lower end of this key and thus prevented further movement of the control bars.

The words and figures representing ten to nineteen are, in the case of the pounds column, arranged on two sections, viz, c, d of the roller 4, and on two sections j, k of the roller 5, so that when the "1" key of the tens of pounds column is depressed all the four sections will be rotated to the amount per-

mitted by the projections 30, 32 simultaneously.

A similar arrangement is provided for the shillings and pence, but as in these cases the numbers required do not go beyond 19 and 11 respectively, all the words and figures are provided on one section only, for the shillings on sections b and h and for the pence on sections a and g. In these cases, therefore, only a single key is required in the tens column. The key 57 in the thousands column for the pounds is similarly constructed to the "1" keys in the tens columns. This key is provided so that when it is desired to print an amount in thousands of pounds without any hundreds a blank space is not left in the wording between the thousands and tens. If, therefore, for example, it were desired to print the amount £1,060 with the corresponding words "one thousand sixty pounds" the key 57 would be depressed. This would allow the control bars 15 for the hundreds and thousands columns for the pounds to be pulled inwards by the springs 19 as far as allowed by the projections 30, 32, then the "1" key in the hundreds column would be depressed, allowing further inward movement until the stop w' came into contact with the lower end of the "1" key, thus preventing further inward movement when the corresponding sections e, f, l, m would have been turned into the required position. The keys for the tens and units columns would then be operated in the manner hereinbefore described.

The key "&" in the tens column of the pounds is used when there are no hundreds or tens (above 19) in a sum such as £1006 or no tens (above 19) as in £106. If one of these sums were required to be printed the corresponding keys would be depressed as hereinbefore described to set the drums in the required positions for "one thousand" and "six" or for "one hundred" and "six" and the corresponding figures. The key "&" would also be depressed and this would cause the section d to be turned so as to bring the word "and" into the printing position, whilst the section k would have an "0" in the corresponding position. The words then printed would be "one thousand and six" or "one hundred and six" as required.

If it were desired to print £6182 the bar controlled by key 6 would be depressed previous to the key controlling 1 and key 8 before key 2, so that the bars for 6 and 8 in the thousands and tens columns would be disengaged from the pins 31 on bars controlled by the keys for 1 and 2 in the hundreds and units columns respectively.

Should it be desired to print £1628, however, the bars 6 and 8 would obviously have to move a greater distance than the bars for 1 and 2. In this instance the bars for 1 and 2 are operated before the bars for 6 and 8. In

order that this may be accomplished the pins 31 on the bars for 6 and 8 are caused to run over the rounded ends of the bars for 1 and 2 in their forward position, causing these bars 5 for 1 and 2 to slightly turn on their pivots 17 sufficiently to allow the pins 31 to pass over the rounded ends. The keys are therefore also of sufficient length and the projections on control bars of sufficient depth to enable this 10 movement to take place without affecting the desired co-operation between the keys and the said projections.

The "1" keys in the tens columns and the key 57 are preferably made shorter than the 15 other keys, so that when in the depressed position they will not project into the path of any of the projections or stops provided on the sides of the control bars 15.

The cheques, dividend warrants or the like 20 to be printed upon are placed on a platen 33 pivotally mounted in the frame 1. The platen is connected by means of rods 34 to cranks 35 keyed to a shaft 36 extending across the machine and operated by a handle 37.

25 In the frame 1 is also mounted a rock shaft 38 on which are keyed two double armed levers 40, one at each end. To the upper arms of these levers are pivoted pawl members 41 which are adapted to engage with pins 42 at 30 the sides of the platen 33 when this is in the raised chain dotted position in Fig. 1. The lower arms of the levers 40 are connected by springs 43 to the frame 1, these springs tending to pull the levers into the full line position. The lower ends of the levers 40 are 35 connected together by a rod 58 extending across the machine. The ends of the levers are provided with slots 62 so as to allow the rod 58 to be moved on guides 44 when the 40 levers are rocked from the full line to the dotted position (Fig. 1) and vice versa. This rod 58 is adapted to co-operate with the arms 18 and serves to bring all the control bars 15 into their normal position with the projections 45 21 engaging with the front plate 22.

To the rock shaft 38 is keyed a crank 45 connected by a link 46 to a crank 47 keyed to a shaft 48 mounted in suitable bearings on the frame 1. On this shaft 48 are also keyed 50 cranks 59 corresponding in number to the number of plates 24. The cranks 59 are adapted to co-operate with pins 60 provided on the plates 24 for the purpose of moving the plates 24 outwards against the action of 55 the springs 25 when the pawls 41 are pulled inwards by the platen, when this is moved into the inoperative inclined position after printing. When the plates 24 are moved outwards in this manner the projections 26 of 60 the keys are released so that the keys can all be returned to their normal raised position by the action of their springs 23.

If just prior to printing it should be noticed that one or more incorrect keys have been 65 pressed for setting the rollers 4, 5, it would be

necessary with the mechanism as hereinbefore described to raise the platen in order to disengage the keys and enable the keys to be reset. In order to avoid this difficulty an auxiliary crank 39 is connected to the shaft 38 by a pin and slot connection 61. By moving this handle in an anticlockwise direction the plates 24 can be moved outwards to release the keys without operating the platen. As the levers 40 will also be moved from 75 their full line to the dotted line position in Fig. 1 the rod 58 acting on the arms 18 will also cause all the control bars 15 to be moved back to their normal positions with their projections 21 engaging the front plate 22, so that they are thus again in a position to be released when the required keys 16 are depressed.

In order that the platen 33 may be operated without disturbing the setting of the keys, 85 when reprinting, for example, springs 63 with bearing rollers 64 are provided at the sides of the frame, and the pawls 41 are lifted by hand above the rollers 64 so as to be retained by them in the raised position. The 90 pawls 41 are prevented from lateral movement by guides 65.

A suitable inking ribbon 49 passes over the rollers 4, 5 between rollers 50, 51 and over 95 guide rollers 52. The rollers 50, 51 are preferably operated in such a manner that when the platen is moved from the printing into the position for receiving a fresh cheque, or the like, the ribbon 49 is advanced in one direction or the other.

The operation of the machine will now be 100 described for printing a cheque for £3624. 18. 10.

All the parts will be in the full line position shown in Fig. 1. In order to bring the sections *c*, *d*, *e*, *f* and *j*, *k*, *l*, *m* of the rollers 4, 5 into the required positions for printing the words "three thousand six hundred twenty four pounds" and the figures "3624," the "3" key, the "6" key, the "2" key and the "4" 110 key in the thousands, hundreds, tens and units columns respectively of the pounds will be depressed, thus releasing the corresponding control bars 15, which will be pulled inwards by the springs 19 until the projections *u*, *r*, *v* and *t* come respectively against the lower ends of the keys *U*, *R*, *V* and *T*. By 115 this movement the racks 14, through the medium of the corresponding members 13, 11, 10, 9, 8, 7 and 6, will have brought the sections *d*, *e*, *f*, *g*, and *j*, *k*, *l*, *m* respectively into the required positions. The keys for the shillings will now be operated in order to bring sections *b* and *h* into the required position for printing the words "eighteen shillings" and the figures "18." For this purpose 120 the "1" key in the tens column for shillings is depressed and by means of its lateral arm allows the control bars 15 for the units and tens shillings to be pulled inwards by their 125 130

springs 19 until the projections 30, 32 on the bars prevent further inward movement. The sections *b* and *h* will now have been turned beyond the position for printing the words 5 "nine shillings" and the figure "9". The "8" key will now be depressed and the two bars 15 will move inwards simultaneously until the projection *p'* on the units bar will have come against the lower end of the key *P*. The racks 10 will now have rotated the sections *b* and *h* into the required position.

It now only remains to set the sections *a* and *g* for printing the words "ten pence" and the figures 10. The "1" key in the tens column for the pence is now depressed and releases both the tens control bar and the units control bar so that these are free to be moved inwards by the springs 19 until stopped by the stops 30, 32. The sections *a* and *g* will 20 thus have been rotated beyond the position for printing the words "nine pence" and the figure 9. The "0" key in the pence units column is now depressed and both control bars will move inwards simultaneously until 25 the stop *x'* comes against the lower end of key *X* when the sections *a* and *g* will be in the required positions.

The depressed keys are now examined in order to ascertain whether the correct keys 30 have been depressed. Should one or more incorrect keys have been depressed then the shaft 38 would be turned in an anticlockwise direction by means of the handle 39 and release all the depressed keys by moving the 35 plates 24 outwards against the action of the springs 25 through the medium of the numbers 45, 46, 47, 48, 59 and 60. At the same time the control bars would be returned to their normal starting position by the rod 58 40 pressing the arms 18 outwards. As soon as the handle 39 is released the springs 43 would move the shaft 38 and the link mechanism operated thereby into the normal position, so that the whole mechanism would be ready 45 for resetting the printing rollers 4, 5.

When the rollers 4, 5 have been set in the required position a cheque is placed on the platen 33 and the latter brought into the vertical position for printing the cheque by moving the handle 37 from the full line position 50 into the dotted position. When the platen 33 reaches the vertical position the pawls 41 will engage with the pins 42 on the platen 33. The platen 33 will then be moved back into 55 the inclined position by moving the handle 37 back into its full line position. The platen 33, during this movement, will pull the pawls 41 into the dotted position, thus turning the shaft 38 so as to operate the link mechanism 60 connected thereto and release the keys and move the control bars back to their starting position for the next setting. Just before the platen 33 reaches the end of its movement 65 the pawls 41 will be disengaged from its pins 42 by the pins 53. The springs 43 will now

return the link mechanism to its starting (full line) position, so that the whole machine will be ready for resetting and printing another cheque.

Should it, however, be desired to print a 70 number of cheques with the same amount, then after the rollers 4, 5 have been set to the required amount, the pawls 41 are brought into engagement with the rollers 65. The platen 33 can now be operated so as to print any required number of cheques without disturbing the setting of the rollers 4, 5 or releasing the keys 16.

Although the mechanism has been described for printing cheques, it will of course 80 be understood that the machine is also applicable for printing dividend warrants, bills, and so forth.

It will also be understood that various 85 modifications may be made without departing from the scope of the invention. For example, the positions of the rollers may be reversed according to the nature of the paper to be printed, and the number and position of the sections forming these rollers may be 90 varied to suit various purposes.

What I claim is:—

1. In a key-operated machine for the simultaneous printing of money values in words and figures, the combination with a pair of complementary printing rollers, of a rack, projections on said rack, gearing between the rack and the printing rollers, a spring for operating said rack, and a plurality of keys, each of said keys when depressed being adapted to release the rack and then to directly limit the movement of said rack by engagement with one of the projections thereon.

2. A key-operated machine as described, comprising a frame, a plurality of printing rollers mounted in said frame, a plurality of spring controlled bars, racks on said bars, gearing between the racks and the printing rollers, said bars being normally held inoperative, projections on said bars, a plurality of 100 depressible keys, each of said keys when depressed being adapted first to depress its corresponding rack so as to render it operative and then to engage with one of the projections thereon so as to limit its movement, a platen 105 pivotally mounted in said frame, and restoring mechanism operable by said platen for returning the keys and bars to their normal position.

3. The combination with a machine as 110 claimed in claim 2 of mechanism for restoring the keys and bars independently of the platen.

4. The combination with a machine as 115 claimed in claim 2 of means for disengaging the restoring mechanism from the platen so as to permit of the operation of the platen for repeat printing.

5. A key-operated machine as described, comprising a frame, a plurality of printing rollers mounted in said frame and arranged 120

- in complementary pairs, a plurality of spring-controlled bars, racks on said bars, bearing between each of said racks and each pair of complementary printing rollers, a plurality of sets of keys, projections on the bars, each 5 of said keys being adapted first to release its corresponding bar and then to limit its movement by engagement with one of the projections thereon, a plurality of spring-controlled plates, one plate being provided for 10 each set of keys and being adapted when one key has been depressed to prevent any of the other keys in the set from being depressed, a platen pivotally mounted in said frame, a rock shaft, cranks on said rock shaft, 15 links connecting the cranks to the platen, a handle on said rock shaft, and restoring mechanism, said restoring mechanism being operated when the platen is moved away from the printing rollers.
- 20 6. A key-operated machine as described, comprising a frame, a plurality of printing rollers, key actuated mechanism for turning said printing rollers in complementary pairs, a platen pivotally mounted in said frame, 25 means for moving the platen towards and away from the printing rollers, a rock shaft, a plurality of arms mounted on said rock shaft, pawls connected to two of said arms, 30 a plurality of pins on the frame and on the platen, the pins on the platen being adapted to be engaged by the pawls when the platen is moved towards the printing rollers, whilst the pins on the frame are adapted to release 35 the pawls from the pins on the platen when the platen nears the end of its movement away from the printing rollers, and link mechanism connected to two other arms on the rock shaft, said link mechanism being 40 adapted to effect the restoring of the key-actuated mechanism and the printing rollers to their normal position.
7. The combination with a machine as claimed in claim 6 of supports, secured to the frame, said supports being adapted to receive 45 said pawls and to hold them out of the path of the pins on the platen.
8. In a key-operated machine as described the combination with a pair of complementary printing rollers, of a pair of sliding bars, 50 a rack on one of said bars, gearing between said rack and said pair of printing rollers, a plurality of keys arranged in two sets, one of said sets of keys being adapted to co-operate 55 with one of said bars, whilst a key in the second set is arranged to co-operate with both bars, projections on said bars, springs attached to said bars, said springs being adapted to move said bars in one direction, said 60 second mentioned key being adapted to release both bars simultaneously, and permit of predetermined movement of said bars by the springs, whilst the depression of one of the first set of keys first releases both bars and 65 then limits the movement thereof.

9. In a key-operated machine as described the combination with a pair of complementary printing rollers, of a pair of longitudinally sliding bars, a rack on one of said bars, gearing between the rack and the printing 70 rollers, projections on one of said bars, each of said bars having two notches therein, a lateral pin on one of the bars, said pin projecting into the path of one of the notches in the second bar, springs connected to said bars, a set of keys for co-operation with the first bar, said keys having their lower ends projecting into the path of the projections, an additional key, a lateral arm on said additional key, said arm extending over the two bars, and a stationary member for engagement with the notches in the bars. 75

10. A key-operated machine as described, comprising a frame, a plurality of printing rollers mounted in said frame, an inking ribbon with means for supporting and guiding same over said printing rollers, key-actuated mechanism for turning said printing rollers into the required position, a platen pivotally mounted in said frame, means for operating said platen, a plurality of spring-actuated plates, said spring-actuated plates being adapted to prevent operation of the key-actuated mechanism after it has been operated, a rock shaft, a plurality of arms on the rock 90 shaft, pawls connected to two of said arms, said pawls being adapted for co-operation with the platen, a second rock shaft, levers on said second rock shaft, said levers engaging with said spring-actuated plates, two arms on the second rock shaft, links connecting said two arms to two of the arms on the first rock shaft, and spring means for returning the rock shafts to their initial position after the pawls are released from the platen. 95

11. In a machine as described the combination with a plurality of complementary printing rollers of a pair of longitudinally sliding bars, racks on each of said bars, two sets of projections on one of said bars, and one set of projections on the second bar, gearing between the racks and the printing rollers, two sets of keys, one set of keys co-operating with one bar and the second set co-operating with the second bar, said keys when depressed being adapted to release said bars and then to limit the movement thereon, the second set of keys including a key adapted to release both bars and enable them to move through a predetermined distance, whilst the subsequent depression of a key in the first set then releases both bars and permits of further movement until it engages with one of the second set of projections on the first bar. 110

12. In a machine as described the combination with a plurality of complementary printing rollers, of a pair of spring-controlled bars, gearing between one of said bars and the printing rollers, and a set of keys and an additional key, said keys being so arranged that 115 120 125 130

when one of the set of keys is depressed one of the bars is released and permits the printing rollers to rotate substantially one half of a revolution, whilst when the additional key is depressed both bars are released and the printing rollers are allowed to rotate just beyond half a revolution, and when one of the first set of keys is subsequently depressed a further partial rotation of the printing rollers in the same direction is effected.

10 13. In a check or like printer, a key board, a series of word printing elements, a series of figure printing elements, means for similarly and simultaneously operating corresponding printing elements of the respective series, including a spring operated element, the keys of said key board being arranged to release said element to the influence of the spring and directly limit its movement under such spring, 15 and means for locking each operated key in position to limit the movement of the said spring operated element.

14. A check or like printer, including printing means adjustable to vary the printing result, automatic means for adjusting the printing means, including a spring operated rack and a member directly connected to the rack, and a series of manually operable elements, each adapted to release said member 20 to permit the racks to move under the influence of the spring, each element serving to correspondingly engage and release said member and to limit the movement of the member for a distance differing from the 25 limitation of every other element.

15. A check or like printer, including printing means adjustable to vary the printing result, automatic means for adjusting the printing means, including a spring operated rack, and a member pivotally connected thereto, means for locking said member to hold the rack against movement, manually operable elements, each adapted to swing the member on its pivot to release it from the 30 lock to thereby permit spring operated movement of the rack, and means carried by the member to automatically engage the operated element to limit the movement of the 35 rack.

16. A check or like printer including printing means to vary the printing result, means for adjusting the printing means including a spring-operated element, and a plurality of manually operable means adapted 40 individually to release the spring-operated element to the influence of the spring and limit the movement of said element under the influence of the spring, each of said manually operable means acting similarly to release 45 the spring operated element and for selectively different limitations in the movement of said element.

In witness whereof I have hereunto set my hand.

EDWARD JOHN WARD.
